UNITED STATES PATENT OFFICE.

FREDERICK O. GRIFFIN, OF OSCEOLA, IOWA.

PACKING-MACHINE FOR SILOS AND THE LIKE.

1,187,304.

Specification of Letters Patent. Patented June 13, 1916.

Application filed November 30, 1915. Serial No. 64,312.

To all whom it may concern:

Be it known that I, FREDERICK O. GRIFFIN, a citizen of the United States, residing at Osceola, in the county of Clarke and State 5 of Iowa, have invented new and useful Improvements in Packing-Machines for Silos and the like, of which the following is a specification.

This invention relates to machines for 10 packing silos and the like, and the main object of the invention is to provide a machine of the class specified comprising separable parts that may be conveniently assembled in a silo for operation and readily 15 dissociated after accomplishment of the work of packing a silo and easily transported from one silo to another.

A further object of the invention is to 20 generally improve the structure of devices of this class and to render them more positive in operation and effective in packing the silage uniformly throughout the interior of a silo through the medium of a tapering roller organization driven by a motor 25 carried on the frame of the machine, and whereby the improved device as an entirety is located within the silo when in working order.

A still further object of the invention is 30 to provide a packing mechanism for silos wherein the main packing organization, or that which comes in direct contact with the silage, extends fully to the center of the silo and may be used in silos varying in diameter, the packing organization having a maximum extent or length to adapt it for 35 use in silos of large diameter and equally efficient in silos of smaller diameter without requiring a readjustment or diminution of 40 the packing organization.

With these and other objects and advantages in view the invention consists in the preferred construction and arrangement of parts which will be more fully hereinafter 45 described and claimed.

In the drawings: Figure 1 is a horizontal section of a portion of a silo showing the improved packing machine disposed therein in top plan view. Fig. 2 is an end elevation 50 of the improved machine showing part of the operating mechanism broken away. Fig. 3 is a longitudinal vertical section of the packing roller organization and supporting frame therefor. Fig. 4 is a transverse vertical section taken in the plane 55 of the line 4-4, Fig. 3. Figs. 5, 6 and 7

are detail perspective views of portions of the roller organization. Fig. 8 is a detail plan view showing a modification of a part of the mechanism. Fig. 9 is a detail elevation of one of the roller sections or members showing a modification in construction.

The numeral 5 designates the main frame comprising longitudinal side beams or bars 6 and end connecting beams or bars 7. 60 These beams or bars 6 and 7 are secured by suitable bolts or other fastenings that may be readily detached so that the frame 5 may be dismantled or the parts thereof dissociated and afterward readily assembled. Near one end of the frame 5 cross supporting beams or bars 8 are applied and may also be readily separated from the beams or bars 6. Secured to one side of the frame 5 and projecting materially in advance of the latter is a supplemental or leader frame 9 comprising beams or bars 10 and 11 secured to the opposite ends of one of the side beams or bars 6 and connected by a brace beam or bar 12. The 70 leader frame 9 is further braced by a beam or bar 13 intersecting the brace beam or bar 12 at right angles and secured at one end to the one side beam or bar 6 and at its opposite end connected to the intersecting ends 75 of the angular beams or bars 10 and 11, or said beam or bar 13 terminates at the apex of the leader frame 9. This frame 9 may have the parts thereof readily separable by using fastening devices of the nut and bolt 80 or other type capable of being easily detached and applied to connect up the several parts of the frame. The main supporting frame 5 will be of a length corresponding to approximately one-half of the diameter 85 of the interior of a silo of maximum size, the inner end of this frame in the operation of the machine extending over the center of the silo when the mechanism is disposed in operative position in the latter. A trav- 90 eling or bearing wheel 14 is suitably mounted at the outer corner of the main frame 5 on the side of this frame opposite that from which the leader frame 9 extends, and at the apex of the leader frame a similar travel 95 wheel 15 is in like manner mounted, said wheels 14 and 15 bearing against the inner surface of the vertical wall of the silo during the operation of the machine to maintain the latter in easy moving 100 relation to the interior of the silo and also to give the machine as an entirety a regular

rotation within and corresponding to the interior contour of the silo. The wheels 14 and 15 engaging the inner surface of the vertical wall of the silo also act to maintain 5 the machine as an entirety in positive position within the silo and rocking or oscillation of the machine is thereby prevented.

As shown by Fig. 8, a slight modification 10 in the traveling or bearing wheel organization is illustrated and is particularly applicable to the apex of the leader frame 9, said modification comprising an angle lever 16 extending over and pivoted at the intersection of the arms 10 and 11 on the apex of 15 the leader frame 9 the end of the shorter arm 16^b of said lever having a cross-arm 17^a pivoted to the end thereof. The cross-arm 17^a has wheels 17 mounted on the ends thereof for engagement with the inner surface 20 of the vertical wall of the silo. A toothed segment 17^b is fixed on the frame 9, and the longer arm 16^a of the lever 16 carries locking means 17^c to engage said segment and whereby the cross-arm 17^a may 25 be adjusted for guiding the machine in different sizes of silos. This modified construction gives a more extended support to the advance end or apex of the leader frame 9, and if desired the same modified structure 30 may be applied in lieu of the wheel 14.

The frame 5 is provided with hangers 18 and 19 depending from opposite ends thereof or from the centers of the transverse beams or bars 7, and in suitable bearings in 35 the ends of these hangers a main shaft 20 is mounted to rotate. Secured on the shaft 20 to rotate therewith is a main packing roller 21 which gradually tapers from the outer toward the inner end thereof and is 40 of less length than the shaft 20. Also mounted on the shaft 20 between the inner reduced end of the main packing roller 21 and the inner hanger 19 are tapered rollers 22 and 23, the latter rollers being free to rotate 45 on the shaft, and the inner end of the roller 22 abuts closely against the outer end of the roller 23. The rollers 21, 22 and 23, together with the frames 5 and 9 and the operating mechanism which will be presently 50 specified, give to the machine as a whole considerable weight which is concentrated on the rollers; and the roller 21, which rotates with the shaft 20, is polygonal in cross-section so as to present a number of 55 flat faces on the outer surface of the roller to the silage, and as a consequence when the roller 21 is rotated through the medium of the shaft 20 the machine as an entirety is caused to revolve within the silo and the 60 said roller may therefore be properly termed not only a packing roller, but also a feeding roller which controls the movement of the machine over the entire silage surface in the silo. The rollers 22 and 23 have 65 smooth outer bearing surfaces and are free

to rotate on the shaft 20 at any speed and in accordance with the movement of the main roller 21 and the machine as an entirety; and by means of the said rollers 22 and 23 there is no crowding or irregular packing 70 of the silage at the center of the mass. The arrangement of the rollers as specified adapts the machine to operate in silos of different sizes, as for instance in a silo having either a 12, 14 or 16-foot diameter. In 75 a silo having a 12-foot diameter the rollers 22 and 23 project beyond the center of the silo and turn backwardly during the forward movement of the main roller 21. In a silo of 14-foot diameter the roller 23 projects over the center and operates or rotates 80 in a direction reverse to the main roller 21 and the roller 22 during the forward movement of the machine; and in a silo having a 16-foot diameter the rollers 21, 22 and 23 85 reach just half-way across the interior of the latter silo. The main roller 21 in addition to its polygonal contour in cross-section, and whereby a number of bearing faces are formed, has a plurality of longitudinally extending ribs 24 running completely from end to end thereof and in the centers of the bearing faces, as clearly shown by Figs. 4 and 6. These ribs 24 give 90 strong tractive characteristics to the main rollers 21 as the ribs take into the silage surface and provide gripping means, as it were, and at the same time the short pieces of silage are drawn under or beneath the main roller as the latter progresses instead 95 of being pushed ahead of the same, and by this means a more even packing of the silage results and at the same time the self-feed of the roller 21 and of the machine as an entirety, through the medium of the said 100 roller, is positive and reliable.

It is proposed to use rollers of different constructions or to make the rollers 21, 22 and 23 of any desired form, but it is preferred that the main roller 21 be composed 105 of separable sections or members each embodying a certain number of components, and in accordance with this preferred construction the said roller 21 is provided with opposite ends of heads 25 and 26 made up 110 of four sections 27 similar in contour in each instance or each being just one-quarter of the head of which it is a part, the sections in the two heads 25 and 26 being exactly the same but differing in size in view of the tapering construction of the roller 21 and the consequent reduced diameter of the inner end or head 26. The sections or segments 115 27 of the heads extend fully into the shaft 20 and each has an outer horizontal key 28 projecting therefrom, and at the periphery each section or segment is also formed with seat grooves 29 parallel with the outer polygonal edges 30 of the section or segment. On the shaft 20 adjacent to the outer end of 120

the latter a key disk 31 is secured and has slots 32 formed therein at diametrically opposite points, and the inner portion of the shaft also has a similar smaller disk 33 which is in like manner formed with slots 34. The slots 32 and 34 of the disks 31 and 33 receive the keys 28 of the sections or segments 27, the latter being located at equal distances from the inner terminals of said sections or segments and providing means for separably holding the parts of the roller in a positive manner.

As shown by Fig. 3, the keys 28 of the sections or segments 27 at the outer end of the roller 21 extend through the slots 32 of the disk 31 from the inner side of said disk outwardly toward the wall of the silo; whereas the keys 28 of the inner head or end 26 of the roller 21 project through the slots 34 of the disk 33 from the inner side of the latter outwardly toward the enlarged end of the roller; and adjacent to the inner head or end 26 a set disk 35 is secured on the shaft 20 which, bearing against the sections or segments of the inner head or end 26, serves to hold the parts of said head or end and the inner end of the roller as a whole in positive assembled relation, and at the same time the set disk 35 provides a space means between the inner end of the roller and the adjacent end of the next roller 22 which is loose on the shaft. The working surface of the roller 21 is composed of a series of plates or strips 36 which have their ends seated in the grooves 29, said plates or strips 36 carrying the longitudinal ribs or projections 24, as clearly shown by Figs. 4 and 6; and when the heads or ends 25 and 26 composed of the sections as specified are assembled in connection with the disks 31 and 33 the plates or strips 36 will be held firmly in place and form engaging faces adapted to come in contact with the silage, and in view of the ribs 24 thereon a positive feed of the roller and of the machine as an entirety will ensue when the shaft 20 is rotated. The roller 21 when constructed as just described may be readily taken apart and assembled as occasion may require in mounting the machine within a silo and to withdraw the machine from the silo for the purpose of transporting it to another similar structure or for storage. It is proposed to form the parts of the machine as thus far described of any suitable material, metal being preferable to give the mechanism as a whole the proper weight to effectively pack the silage within a silo.

As shown by Fig. 1, the outer end of the main packing and feed roller 21 is located a considerable distance from the inner surface of the vertical wall of the silo and without provision of means which will be presently explained the silage falling in between the said end of the roller and the

wall of the silo would remain loose, and to compensate for this space a packing wheel or roller 37 is mounted on a shaft 38 engaging suitable bearings on the beams or bars 10 and 12 of the leader or supplemental frame 9, the shaft 38 being disposed at such angle relatively to the frame 9 as to cause the wheel to run closely to the inner surface of the vertical wall of the silo and fully cover the space that is left unengaged by the roller 21. The roller or marginal packer 37 runs loose on the shaft 38, and the weight of the supplemental frame 9 is imposed on the shaft 38 and said roller 37 and thereby sufficient pressure is given to the silage engaged by the roller 37 that will result in a tight packing of the silage engaged by the said latter roller.

The shaft 20 is operated through the medium of a suitable motor 39, preferably of the electrical type, and which is mounted on the supporting beams or bars 8, the shaft 40 of this motor being provided with a suitable sprocket wheel 41 engaged by a sprocket belt 42 which in turn engages a sprocket wheel 43 on the inner end of a transmission shaft 44 mounted in suitable bearings in the beams or bars 8 and the outer transverse beam or bars 7. The shaft 44 projects outwardly beyond the outer beam or bar 7 and is provided with a sprocket wheel 45; and on the adjacent end of the shaft 20 is a sprocket wheel 46, a chain belt 47 being trained over the two sprocket wheels 45 and 46 and by this means the shaft 20 is regularly driven from the motor. The motor may be of any preferred type, and it will also be understood that any mechanism other than that specified might be adopted for rotating the shaft 20, but it is preferred that the machine be equipped with such form of operating mechanism that it will be unnecessary to extend any part of the mechanism for imparting motion to the shaft 20 outside of the silo. It is obvious that a well known form of gasoline engine or motor may be used for driving the mechanism where electric current is inaccessible.

Instead of the plates or strips 36, which as shown by Fig. 4 are three in number in engagement with each section or segment 27 of the heads, a galvanized sheet iron or other sheet metal section 48 may be used and suitably bent into shape to provide ribs or corrugations 49 therein, as shown by Fig. 9, four of these sheet metal surface sheets being used to complete the drum or roller 21 and having their ends fitted in the grooves 29 of the segments of the heads. The weight of the drum or roller 21 may be increased at will through the medium of tanks 50 secured to each quarter-section of the main drum or roller 21 between the heads 25 and 26 and suitably connected to the parts without interfering with the ready separation.

thereof. These tanks 50 preferably fill the space within the main drum 21 and have the same tapering contour as the latter. Each tank is provided with means for introducing 5 water or sand therein. It will be understood that the weight of the main drum 21 can thus be modified at will to regulate the pressure thereof relatively to the material operated upon as may be found necessary.

10 From the foregoing it will be seen that a packing machine of a convenient type for use in silos is provided and capable of having its parts separated and associated as circumstances may demand, particularly to accommodate various sizes of openings or inlets of 15 silos. In some silo structures the doors project inside, and under such conditions it would be preferable to use the form of travel, bearing or guiding wheels as shown by Fig. 8 and carried by the pivoted beam or arm 16 so that one wheel will pass over the projecting door in advance of the other and a positive guiding action thus result without material jar; whereas when a single wheel is 20 used, as shown by Fig. 1, there might be considerable jar by the wheel engaging the door projections. It will also be understood that the operating mechanism will be 25 properly proportioned to give the speed of rotation desired to the shaft 20. While the parts 21, 22 and 23 have been described as 30 rollers, they may also be considered as drums which operate to pack the silage which they engage.

35 Changes in the proportions, dimensions and minor details may be adopted without departing from the spirit of the invention.

What is claimed is:

1. In a packing machine for silos and the 40 like, a frame, a driven shaft carried by the frame, a main tapered drum carried by and fixed to said shaft to rotate with the latter, and smaller tapered drums loosely mounted on the inner extremity of the shaft.

2. In a packing machine for silos and the 45 like, a frame, a driven shaft carried by the frame, a main tapered drum polygonal in cross-section and fixed on said shaft to rotate with the latter to provide both a packing 50 and machine progressing means, and smaller tapered drums loosely mounted on the inner extremity of the shaft.

3. In a packing machine for silos and the 55 like, a main positively driven tapered packing drum having a polygonal contour in cross-section and provided with tractive faces, and smaller tapered drums adjacent to the inner extremity of the main drum and having a loose rotative movement.

60 4. In a packing machine for silos and the like, a main positively driven tapered packing drum having a polygonal surface to provide tractive faces, a frame carrying said drum, and driving mechanism for the drum, 65 the said drum also operating to progressively

move and to carry the frame and driving mechanism therewith.

5. In a packing machine for silos and the like, a main positively driven tapered packing drum having a polygonal surface to provide tractive faces, the said faces having central longitudinally disposed ribs, a frame carrying said drum, and driving mechanism for the drum. 70

6. In a packing machine for silos and the like, a driven shaft, a main positively driven tapered packing drum keyed on the shaft, the drum having readily separable and associable components consisting of end heads made up of a series of segments and flat 75 plates or members engaging and extending between said heads, and means on the shaft for engaging portions of the said heads. 80

7. In a packing machine for silos and the like, a driven shaft, a main tapered packing 85 drum keyed on the shaft, the drum having readily separable and associable components consisting of end heads made up of a series of segments having keys projecting therefrom and flat plates or members terminally 90 engaging the heads near the peripheries of the latter, and means on the shaft to separably receive the keys of the segments.

8. In a packing machine for silos and the like, a driven shaft, a main drum keyed on the shaft, the drum having readily separable 95 and associable components consisting of end heads made up of a series of segments having keys projecting from one side and seat grooves also formed therein with flat plates 100 or members terminally engaging said grooves, and means on the shaft to separably receive the keys of the segments.

9. In a packing machine for silos and the like, a driven shaft, a main tapered packing 105 drum keyed on the said shaft, the drum having readily separable and associable components consisting of end heads made up of a series of segments having keys projecting therefrom and flat plates or members 110 terminally engaging the heads, and disks secured on the shaft and provided with opposed slots to separably receive said segment keys.

10. In a packing machine for silos and the 115 like, a driven shaft, a main tapered packing drum on the shaft and comprising heads having separable segments with keys projecting from one side and grooves near the peripheries in the opposite side and flat 120 plates or members between the heads engaging said grooves, the plates having outer longitudinally extending ribs, and means secured on the shaft to separably receive the 125 said keys.

11. In a packing machine for silos and the like, a frame composed of separable parts and carrying a shaft, a main packing roller made up of separable parts and secured on the shaft, smaller tapered rollers loosely 130

mounted on and separable from the shaft, and mechanism for driving said shaft.

12. In a packing machine for silos and the like, a main frame having a leader frame 5 connected thereto, a shaft carried by the main frame, a packing drum mounted on said shaft, mechanism for operating the shaft, and a marginal packing roller carried by the leader frame.
- 10 13. In a packing machine for silos and the like, a main frame having a leader frame connected thereto, a shaft carried by the main frame, fast and loose packing drums on the said shaft, a marginal packing roller 15 carried by the leader frame, guide rollers on the main and leader frames, and mechanism for driving said shaft.

14. In a packing machine for silos and the like, a main frame having a leader frame 20 connected thereto, a shaft carried by the main frame, fast and loose packing drums on the said shaft, a marginal packing roller carried by the leader frame, a guide roller at the one outer corner of the main frame, a 25 pair of spaced guide rollers pivotally carried by the leader frame, and mechanism for operating said shaft.

15. A packing machine for silos and the like having a driven shaft, a main packing 30 drum fixed to the shaft to rotate therewith, and smaller drums loosely mounted on the shaft and free to rotate in the same or in a direction opposite to the direction of rotation of the main drum.

- 25 16. A packing machine for silos and the like having a driven shaft, a main packing drum fixed to the shaft to rotate therewith, and a marginal packing roller mounted to coöperate with the packing drum to engage 40 the material which is cleared by the outer extremity of the drum.

Copies of this patent may be obtained for five cents each, by addressing the "Commissioner of Patents, Washington, D. C."

17. In a packing machine for silos and the like, a driven shaft, a main packing drum fixed to the shaft to rotate therewith, smaller drums loosely mounted on the shaft and 45 free to rotate in the same or in a direction opposite to the direction of rotation of the main drum, and a marginal packing roller mounted to coöperate with the said drums and to engage the material to be packed 50 which is cleared by the outer portion of the main drum.

18. In a packing machine for silos and the like, a driven shaft, a main packing drum fixed to and rotatable with the shaft, smaller 55 drums loosely mounted on the inner extremity of the shaft and free to rotate on the latter, and a marginal packing roller mounted to coöperate with the said drums and engage the material to be packed beyond the outer 60 end of the main packing drum.

19. In a packing machine for silos and the like, a driven shaft and a main packing drum fixed to and rotatable with the shaft and embodying therein a series of weight 65 tanks for receiving material to increase the pressure force of the drum.

20. In a packing machine for silos and the like, a main positively driven packing drum comprising readily separable and associable 70 components consisting of end heads made up of a series of segments and devices between the said segmental heads to provide a pressing surface for the drum, and means for operating the drum. 75

In testimony whereof I have hereunto set my hand in presence of two subscribing witnesses.

FREDERICK O. GRIFFIN.
